CHILD'S DRESS

Eden Kelley, 1050 Park Ave., New York, N.Y.

Original design application Mar. 29, 1960, Ser. No. 59,928. Divided and this application Mar. 13, 1962, Ser. No. 69,242

Term of patent 14 years

(Cl. D3—26)

FIG. 1.

FIG. 2.

FIG. 3.

FIG. 4.

FIG. 1 is a rear perspective view of a child's dress showing my new design, the front of the child's dress being conventional in appearance;

FIG. 2 is an end view of the wing-like decoration shown in FIG. 1;

FIG. 3 is a plan view of the wing-like decoration shown in FIGS. 1 and 2; and

FIG. 4 is a plan view of a modified form of wing-like decoration wherein a pleated fabric is employed.

The dominant feature of my design resides in the wing-like decoration shown in full lines.

The present application is a division of Serial No. D-59,928, filed March 29, 1960.

I claim:

The ornamental design for a child's dress, substantially as shown and described.
